(57) **CLAIM**

The ornamental design for a handle as shown and described.

DESCRIPTION

FIG. 1 is a top, perspective view of a handle showing my new design;

FIG. 2 is a bottom, perspective view thereof;

FIG. 3 is a top view thereof;

FIG. 4 is a bottom view thereof;

FIG. 5 is a right side view thereof, the left side view being a mirror image thereof; and,
FIG. 6 is a front view thereof, the rear view being a mirror image thereof.

The drawings include surface shading which illustrates contour, not surface ornamentation.
